UNITED STATES PATENT OFFICE.

JONATHAN WAINWRIGHT AND J. GILBERT WAINWRIGHT, OF WAUKEGAN, ILLINOIS.

HORSE-COLLAR AND HAME.

SPECIFICATION forming part of Letters Patent No. 374,328, dated December 6, 1887.

Application filed May 7, 1887. Serial No. 237,659. (No model.)

To all whom it may concern:

Be it known that we, JONATHAN WAINWRIGHT and J. GILBERT WAINWRIGHT, citizens of the United States, residing at Waukegan, in the county of Lake and State of Illinois, have invented certain new and useful Improvements in Horse-Collars and Hames; and we do declare the following to be a full, clear, and exact description of the invention, 10 such as will enable others skilled in the art to which it appertains to make and use the same.

Our invention relates to certain novel improvements in the manufacture of horse-collars and the fastenings therefor, which improvements will be fully understood from the following description and claims when taken in connection with the annexed drawings, in which—

Figure 1 is a perspective view of a metal horse-collar rim provided with a spring-latch throat-fastening. Fig. 2 is a perspective view having a part broken away, showing a wooden hame and horse-collar rim combined, provided with the same throat-fastening as shown in 25 Fig. 1. Fig. 3 is an enlarged perspective view of parts of the metal horse-collar rim, indicating more clearly the construction of the throat-fastening. Fig. 4 is a perspective view of the spring-latch for connecting the throat 30 ends of the collar. Fig. 5 is a perspective view of a metal hame and horse-collar rim combined, provided with loops at the upper ends for the use of connecting straps. Fig. 6 is a perspective view, detached, of my improved metal locking device for a leather horse-collar rim. Fig. 7 is a diametrical section of the locking device connected. Fig. 8 is a perspective view detached, illustrating a modified form of Figs. 6 and 7.

Referring to the annexed drawings by letters, A A' designate the two sides or halves of a metal horse-collar rim, which are each constructed with a concavo-convex portion, *a*, and with a skeleton flange, *b*, through which are numerous apertures for the purpose of receiving stitches that secure the rims to the bellies of the collar *B*. The said rims have tug-eyes *c*, formed integral with them, and they are also provided with eye-guides *d*, suitably attached 50 to them for the passage of the reins. At the

lower or throat end of the half *A* is formed a flange, *e*, terminating in a vertical recess, *e'*, and upon said flange *e* is riveted, at *f*, a spring-latch, *f'*, provided with a finger-piece, *f''*, and also with a pintle, *g*. The extremity of the other half, *A'*, is shouldered and provided with a perforated tenon, *g'*, adapted to be received in the recess *e'* and to be locked therein by the pintle *g* on the spring *f'*.

The upper part of the collar may be permanently united, or it may be united by straps or other suitable fastenings.

The above-described fastening is especially designed for metal horse-collar rims. For leather horse-collar rims I employ thimbles *G G'* for the detachable throated ends thereof, as shown in Figs. 6, 7, and 8. These thimbles have slots *h* in them for the edges of the leather rims to pass through, and the thimbles are secured permanently to the lower ends 70 of the collar by rivets or other suitable means.

The thimble *G* is constructed with a recess or perforation in its end, and is provided with a locking-spring, *f'*. The thimble *G'* is constructed with a tenon protruding centrally 75 from its end, adapted to enter the recess or perforation in the end of the thimble *G*. This thimble *G'* is also perforated to receive the locking-pin on the spring *f'* when the two thimbles are brought together and locked at 80 the throat of the collar.

Having described our invention we claim—

As an improved article of manufacture, a horse-collar consisting of the hame-sections *B*, the concavo-convex metal rims receiving 85 the said sections and having flanges provided with apertures, as shown, and their throat ends extending beyond the throat ends of the said hames, and one end terminating in a socket, *e'*, and the other end terminating in a 90 perforated tenon, *g'*, and a fastening, *f'*, having a stud at its outer end to enter the perforation of the said tenon, substantially as specified.

In testimony whereof we affix our signatures in presence of two witnesses.

JONATHAN WAINWRIGHT.
J. GILBERT WAINWRIGHT.
